UNITED STATES PATENT OFFICE

DON R. SEELY, OF SALT LAKE CITY, UTAH, ASSIGNOR TO THE UTAH RADIO PRODUCTS COMPANY, OF SALT LAKE CITY, UTAH, A CORPORATION OF UTAH

ACOUSTIC DIAPHRAGM AND MOUNTING

Application filed August 20, 1928. Serial No. 300,748.

This invention relates to a diaphragm and mounting, and its principal objects are to provide:

First. A diaphragm capable of producing or reproducing sounds having frequencies extending over a wide range.

Second. One which shall give forth rich mellow tones.

Third. A wooden diaphragm which shall be strong, durable, and moisture-resistant, and thus be suited to varying climatic conditions.

In the quest of an improved material for diaphragms, particularly of the kind used for radio loud speakers, I have found that wood has properties which are particularly suited to give forth rich, mellow sounds. The wood may be of different kinds, such as pine, spruce, birch or the like, cut into thin sheets.

The ratio of the thickness of a sheet of the wood, to the area of the finished diaphragm, forms an important part of the invention. This ratio varies between certain limits, but its maximum I place at one eighth of an inch per square foot of area of the finished diaphragm. As a rule, however, this ratio may be considerably less.

The superficial shape of the diaphragm may be round, square, elliptical, oblong or otherwise, so long as the conditions for proper vibratory motion are maintained.

Thin sheets of wood when first formed, give quite satisfactory results when used as diaphragms, but very soon, the contraction, due to the seasoning manifested when freshly cut wood fibers are exposed to the atmosphere, cause objectionable cracks and checks to appear, which of course impair the desirable properties of the wood, and soon render the untreated wood diaphragm unfit for service.

The treatment accorded the wood sheets, by means of the present invention, gives a high degree of permanence to the desirable acoustic properties originally possessed by the wooden sheets, and preserves their capability to give forth the peculiarly rich and mellow tones which may originally emanate therefrom. My aim is to interfere as little

as possible with the acoustic properties of the wood in the condition when first cut into thin sheets, but at the same time to give the sheets such structural support, strength and toughness, as shall insure their durability. In many cases, my treatment improves the natural acoustic properties of the wood.

To this end, the sheets of wood are impregnated with a nitrocellulose solution, for instance, ambroid, which after the evaporation of the volatile constituents thereof, leaves the resinous fibers of the wood cemented together. This cementing is effected by the tough, flexible and waterproof residue permeating the pith of the wood after the said evaporation. The wood, further, may be covered with a textile fabric, for example, cambric, whose threads in the warp and woof are preferably placed substantially diagonal with the grain of the wood. The cloth may be cemented or glued to the wood, and both the wood and the cloth impregnated with the nitrocellulose solution.

If desired, the wood may be first impregnated with the nitrocellulose solution, and the cloth be cemented thereto by laying the cloth on the wood and applying a coat of the said solution. After the application of the nitrocellulose solution the sheets may be subjected to suitable pressure, applied by means of presses similar to those used in the ordinary laminating of wood for panels and the like.

If found advantageous, the cloth may be applied to the wood sheets in strips or ribbons rather than in continuous layers, these strips being applied either to one or both surfaces of the wood, and running in one direction on one side of the sheet, and in the transverse direction on the other side of the sheet, or the strips may be criss-crossed in two series, one series being on each surface.

In use, the diaphragm may be supported by a wooden frame conforming to the superficial shape of the diaphragm, said frame having a depth transverse to the surface of the diaphragm sufficient to insure rigidity, and also to form a cabinet or other structure for concealing the loud speaker actuating unit, which latter may be of any desired type in ordinary use.

The features of this invention for which the protection of Letters Patent of the United States is desired, are collectively grouped in the claims concluding this specification.

5 In the drawing, which illustrates merely one embodiment of this invention,

Fig. 1 represents a rear elevation of a loud speaker whose equipment includes my improved diaphragm and its mounting;

10 Fig. 2, a section on line 2, Fig. 1;

Fig. 3, a rear elevation, parts being omitted;

Fig. 4, a minor detail;

15 Figs. 5 and 6, fragmentary elevations showing variations in the structural constitution of the diaphragm proper; Fig. 5 being a front elevation and Fig. 6 a rear elevation reflected from a mirror plane; and

20 Fig. 7, a fragmentary cross-section in diagram, greatly enlarged, to show the theoretical structure of this improved diaphragm.

Referring to the drawing, 10 indicates a frame of substantially square superficial configuration, made up of the individual members 12, which may be mitered together at the 25 corners as indicated at 14.

The diaphragm is indicated at 15, and this may be attached to one face of the frame in any suitable manner, such as by gluing or cementing.

30 Either one or both of the superficial surfaces 16 and 17 of the diaphragm may be covered with a thin textile fabric such as cambric, applied diagonally with respect to the direction in which runs the grain of the wood at the faces of the diaphragm, somewhat after the manner indicated at 18 and 19 in Figs. 1 and 3, the grain of the wood being assumed to run as indicated by the double-pointed arrow 24. The layers of cloth, 18 and 40 19, may be cemented to the wooden sheet 15 before the latter is attached to the frame 10, and both surfaces may be treated with amberoid or other nitrocellulose solution, either before or after the diaphragm is applied to the 45 frame 10.

50 In order to stiffen the diaphragm and to improve its vibratory qualities, diagonal ribs 20 of wood or other suitable material, may be attached to one face of the diaphragm, and other ribs 21 of similar material may be applied transverse to the grain of the wood of the diaphragm.

Inside of the frame 10 may be blocks 25, to 55 which is attached the cross-piece 26, the latter being spaced apart from the diaphragm 15 sufficiently far to clear the ribs 20 and 21. On the cross-piece 26 is mounted any desired vibratory actuating unit 27, such as one of the well known electromagnetic push-and-pull type. This unit may be held in place by means of the strap 28.

60 Strap 28 engages the bolts 29, the latter being fastened in the base 30, which in turn may be attached to the cross-piece 26 by 65 means of the screws 31. The armature 40 of

the actuating unit may be connected to the diaphragm 15 by means of the usual pin 41.

As a modification, the diaphragm may have the strips 32 and 36 attached to one side thereof by means of the nitrocellulose solution, and the strips 34 and 38 to the other side, these strips being substantially diagonal to the grain of the wood, which is assumed to extend in the direction indicated by the arrows 35. It is evident that the strips 32 or 38 as the case may be, might be omitted, thus leaving only one series of strips on each side of the diaphragm, these two remaining series of strips however, being preferably transverse to each other. 70 75 Taking the small circle 42 as a point of reference, it will be noted that the strips 32 and 36 alternate with strips 34 and 38 respectively, in relative positions.

80 The wood sheets may be single in ply, or they may be laminated so as to be composed of two or more plies. In a multiple-ply sheet, the directions of the grains of the individual plies would be perpendicular to each other or to one another, as the case 85 might be, but the warp and woof of the cloth, if used, would nevertheless be substantially diagonal to the grain of the face laminations.

90 It is to be understood that the textile fabric is not used in all cases, as the treatment of the wood with the nitrocellulose solution alone adds strength and durability to the wood. However, in cases where still greater strength and durability are desired, 95 the textile fabric is employed.

100 In Fig. 7 is indicated the structure of this improved diaphragm in accordance with its fundamental theory. The pith 49 is saturated with the nitrocellulose solution, which 105 latter upon evaporation of its volatile constituents, leaves the pith permeated with the tough, solidified constituents of the nitrocellulose solution. The solidified constituents 110 serve to flexibly cement the resinous fibers or minute tubes 50 of the wood together, thus producing a durable material for diaphragms. The optional covering of cloth for the superficial faces of the wood sheet, as hereinbefore mentioned, is indicated at 18 and 19 (Fig. 7).

115 In the present instance, each side of the square inside the frame 10 might be one foot long, in which case the dimension 51 120 in Fig. 7, would be one-eighth inch or less.

125 While a specific embodiment of this invention is herein shown and described, it is to be clearly understood that variations within the scope of the accompanying claims, may be resorted to without jeopardizing my patent protection.

Having fully described my invention, what I claim is:

130 1. An acoustic diaphragm formed of a

- sheet of wood which has been impregnated with a nitrocellulose solution.
2. An acoustic diaphragm formed of a sheet of wood in which are retained the solidified constituents of a nitrocellulose solution.
3. An acoustic diaphragm formed of a sheet of wood which has been impregnated with a nitrocellulose solution, and having cloth cemented to the superficial surface of said sheet.
4. An acoustic diaphragm formed of a sheet of wood in which are retained the solidified constituents of a nitrocellulose solution, and having cloth cemented to the superficial surface of said sheet.
5. An acoustic diaphragm formed of a sheet of wood which has been impregnated with a nitrocellulose solution, and having cloth cemented to the superficial surface of said sheet, said cloth having its warp and woof in diagonal relation to the grain of the said wood sheet.
6. An acoustic diaphragm formed of a sheet of wood in which are retained the solidified constituents of a nitrocellulose solution, and having a textile fabric cemented to the superficial surface of said sheet, said textile fabric having its warp and woof in diagonal relation to the grain of the said wood sheet.
7. An acoustic diaphragm formed of a sheet of wood, and a layer of textile fabric attached to the superficial surface of said wooden sheet, the warp and the woof of the said textile fabric being substantially diagonal to the grain of the said wooden sheet.
8. An acoustic diaphragm composed of wood less than one-eighth inch in thickness for each square foot of superficial area of the said diaphragm, said wood having been impregnated with a solution of nitrocellulose.
9. An acoustic diaphragm comprising a sheet of wood having a thickness one-eighth inch or less for each superficial square foot of area of the said diaphragm, and a mass of the solidified constituents of a nitrocellulose solution permeating the sheet.
10. An acoustic diaphragm comprising a sheet of wood one-eighth inch or less in thickness for each superficial square foot area thereof, and a layer of textile fabric attached to the said sheet, the warp and woof of the textile fabric being substantially diagonal to the grain of the said wood.
11. An acoustic diaphragm comprising a sheet of wood, a textile fabric cemented to the face of the said sheet, the warp and the woof of the said textile fabric being substantially diagonal to the grain of the said wood, and a nitrocellulose residue in a cemented relation to the said textile fabric and the said wooden sheet.
12. An acoustic diaphragm comprising a sheet of wood, a nitrocellulose residue per-
- meating the said wood, and a textile fabric cemented to the surface of the said wood.
13. An acoustic diaphragm comprising a sheet of wood, layers of textile fabric cemented to the face of the said sheet, the warp and the woof of the said textile fabric being substantially diagonal to the grain of the said wood, a nitrocellulose residue permeating said diaphragm, a frame having a configuration corresponding to the contour of the said diaphragm, said diaphragm attached to said frame, and means for operably mounting an actuating unit within said frame in a manner such that said unit may be connected to said diaphragm.
14. A wooden diaphragm having a thickness less than one-eighth inch for every square foot of superficial area of said diaphragm, a frame having a configuration corresponding to the perimeter of said diaphragm and rigidly fastened to said frame along said perimeter, the members of said frame being substantially transverse to the surface of said diaphragm, and having their outer surfaces flush with the edges of said diaphragm, and means for operably mounting an actuating unit for said diaphragm within said frame.
- In testimony whereof I sign my name hereto.
- DON R. SEELY.
